UNITED STATES PATENT OFFICE.

NEWTON J. BISHOP, OF ST. LOUIS, MISSOURI.

CURTAIN-ROD BRACKET.

Application filed October 9, 1922. Serial No. 593,329.

To all whom it may concern:

Be it known that I, NEWTON J. BISHOP, a citizen of the United States, residing at St. Louis, in the State of Missouri, have 5 invented a new and useful Curtain-Rod Bracket, of which the following is a specification.

This invention relates to curtain rod brackets.

10 The object of the invention is to provide a simple and efficient attaching bracket for mounting a curtain rod on a window frame without marring it in any way.

With the foregoing and other objects in view which will appear as the description proceeds, the invention resides in the combination and arrangement of parts and in the details of construction hereinafter described and claimed, it being understood 20 that changes in the precise embodiment of the invention herein disclosed may be made within the scope of what is claimed without departing from the spirit of the invention.

In the accompanying drawings:—

25 Figure 1 represents a front elevation of a rod supported by brackets constructed in accordance with this invention, shown applied, the curtain being omitted.

Fig. 2 is a horizontal section through the 30 window frame with the rod brackets shown applied and in plan, and

Fig. 3 is a detail perspective view of the bracket constituting this invention.

In the embodiment illustrated, the curtain rod comprises a heavy wire 1 with eyes 35 2 and 3 at its opposite ends with which are connected heavy coiled springs 4 and 5. These springs 4 and 5 are also provided with terminal eyes, those at one end being engaged with the eyes 2 and 3 of the rod 1 and those at the other end being connected with attaching brackets 6 and 16 which will 40 presently be described.

Each of these brackets is exactly alike in 45 construction, and hence only one will be described in detail.

The bracket 6 which like bracket 16 is composed of a single piece of stiff wire bent to form a substantially triangular body 7 50 which is designed to lie flat against the front face of the window frame with the

pointed ends 12 thereof facing inwardly or toward each other. One end 8 extends laterally outward from about midway the length of the base of said member and in the same plane and is provided at its end with an inturned pointed hook 9 adapted to be engaged with the edge of the window frame as is shown clearly in Figs. 1 and 2.

The other end member of the wire is 60 looped around the member 8 as shown at 8^a and extends in a plane at right angles to the member 8, forming an outstanding supporting rod 10 equipped at its free end with an eye 11 with which the eye at the other end of the spring at that side of the frame is designed to be engaged. In the application of this rod, the brackets 6 and 16 are laid with the body members 7 flat against the outer faces of the opposed sides 70 of the window frame as shown in Figs. 1 and 2, with their elongated pointed ends extending inward and the hooks 9 at their diametrically opposite sides embedded in the side edges of the frame. This mounting of 75 the brackets operates to place the rod 1 under tension so that it will be held taut to support the curtain to be mounted thereon and the pull being on the bases of the triangles will cause the pointed ends 12 to operate as fulcrums and together with the wings on opposite sides of the median line thereof operate to prevent turning of the bracket under strain and the consequent pulling out of the hooks 9.

The stiff coiled springs 4 and 5 obviously may be stretched to adapt the rod to fit windows of varying widths without necessitating any adjustment of the parts. This rod may be cheaply constructed and sold at 90 a low price and will not noticeably mar the window frame on which it is mounted, being easily applied and removed without requiring any nails, screws or the like.

I claim:—

A rod supporting bracket of the class described comprising a single piece of wire bent to form a substantially triangular body with an arm extending longitudinally therefrom in the same plane midway one side of 100 said triangle and equipped with a frame engaging hook, and a second arm extending

in a plane at right angles to the first mentioned arm and coiled at its base to provide an eye through which said first mentioned arm extends, said second arm having an eye 5 at its free end to receive the rod to be supported, the two remaining sides of the triangle meeting at a point located opposite and remote from the junction of said arms.

In testimony that I claim the foregoing as my own, I have hereto affixed my signature in the presence of two witnesses. 10

NEWTON J. BISHOP.
